UNITED STATES PATENT OFFICE.

JAMES M. WEER, OF SCHENECTADY, NEW YORK, ASSIGNEE TO GENERAL ELECTRIC COMPANY, A CORPORATION OF NEW YORK.

INDUCTION FURNACE.

Application filed April 19, 1923, Serial No. 383,293. Renewed August 10, 1927.

This invention relates to induction furnaces of the repulsion type such as described in the Transactions of the American Electrochemical Society, Vol. XLII, 1922, page 233, in which circulation of the fluid charge is caused by the electro-magnetic reaction between the primary winding and the secondary current carrying elements of the fluid charge, differences in fluid pressure between current carrying elements which are more and less remote from the primary, resulting from this reaction, being utilized to produce the desired circulation. It is the object of my present invention to provide for a more uniform variation of fluid pressure throughout the secondary, to secure a better power factor and to improve regulability of the furnace.

In the constructions shown and described in my prior application, Ser. No. 525,660, filed Dec. 29, 1921, where adjacent surfaces of the primary and secondary are parallel to each other, the differences in fluid pressure are obtained by a parallel displacement between primary and secondary. For instance, in the preferred embodiment shown on page 234 of the above article, the primary and secondary are both cylindrical in shape and have a common axis, but are displaced with respect to one another along the axis, giving maximum pressure at that end of the secondary cylinder which is more remote from the primary winding by reason of the displacement, and minimum pressure at the other end, which is nearer to the primary. In my present invention, I have provided an improved construction in which the adjacent surfaces of primary and secondary are not parallel, the differences in fluid pressure being obtainable without displacement, by making the primary, or secondary, or both primary and secondary, of a dished or frusto-conical shape. One end of a transverse section of the secondary is more remote from the primary winding than the other by reason of the respective shapes of the primary and secondary.

Of the accompanying drawings, Fig. 1 is a vertical section of a preferred form of furnace embodying my present invention; Figs. 2 and 3 are similar sections of modifications of the same form of furnace as shown in

Fig. 1; Figs. 4, 6 and 7 are vertical sections of other embodiments of my invention; and Fig. 5 is a horizontal section taken through the lines 5—5 of Fig. 4.

Referring particularly to Fig. 1, the refractory charge container or crucible of a furnace embodying my invention is constituted by interlocking fitted members 2, 3 and 4, surrounded by a heat insulating packing 5 and a metal frame 6. The members 2, 3 and 4 may consist of fire clay or particles of fused magnesite bonded together with a suitable binder, such as magnesium chloride, and are fashioned and fired before assembly in the furnace. A cover 7, a charging door 8, and a spout 9 are provided as usual.

The members 2 and 3 are nested together with cemented joints, to provide a looped cavity 10 which communicates by the conduits 11 and 12, with a reservoir 13 provided by the cylindrical member 4 which is fitted and cemented to the member 3. A magnetic core 14 is interlinked with the secondary coil 10. A cylindrical primary inducing winding 15 is placed upon the upper leg of the core which is threaded through the secondary loop, and is arranged coaxially with the secondary loop 10. A lining 16 for the opening through the crucible member 2 preferably is provided to protect the winding 15 in case of a break in the member 2 which would permit the escape of liquid charge.

It will be observed that the member 2 is of progressively decreasing thickness, from left to right along its axis, making the chamber 10 frusto-conical in shape. The portion of the liquid charge secondary which is adjacent to the conduit 12 is nearer to the primary coil than the portion at the opposite end of the section of the secondary, which communicates with the conduit 11. The pressure at the end of the secondary most remote from the primary being greater than the pressure at the end nearer the primary, the charge is ejected from the secondary into the reservoir through the channel 11 and a return flow occurs into the secondary through the channel 12. Due to the gradual variation of the distance between primary and secondary, the fluid pressure in the secondary 10, caused by electromagnetic repulsion between the primary and secondary,

will have a gradual variation from one end of the secondary to the other. That is, in the furnace shown in Fig. 1, there is present during operation a fluid pressure which gradually increases from right to left. This pressure may be regulated by axially displacing the primary winding 15 along the core 14; for example, a movement of the primary winding to the right will intensify the difference in the fluid pressure in opposite ends of the secondary and a movement of the primary coil to the left will decrease the difference in pressure between these two regions.

15 In some cases it is advantageous to make the cavity containing the molten charge constituting the secondary, of uniform diameter and to construct the primary winding of the frusto-conical or dished shape, as shown in Fig. 2. The primary winding is here designated as 17 to distinguish it from the winding 15 of Fig. 1.

In the construction shown in Fig. 3, both the secondary 18 and the primary 19 are made of frusto-conical shape, the wider ends of the two cones facing in opposite directions. In the modification shown in Fig. 2 the pressure will be maximum at the left side of the secondary 20 which is furthest away from the primary and the flow of liquid charge will occur through the channel 21 returning through the channel 22. In the modification shown in Fig. 3 the flow will occur in the opposite direction, that is, from the channel 23 back through the channel 24.

In the modification of my invention shown in Figs. 4 and 5, the primary winding 25 is disc-shaped while the secondary 26 is frusto-conical or dished in shape. The complete circuit current-carrying elements of the secondary 26 adjacent to its inner periphery are more remote from the primary than those adjacent to the outer periphery. Maximum fluid pressure, therefore, is set up at the inner periphery with a flow from the secondary at 27 through the conduit 30 into the reservoir 31 accompanied by a return flow through the conduit 32 into the secondary at its outer periphery at 28.

In the modification shown in Fig. 7, the secondary 33 is disc-shaped, and the primary 34 is frusto-conical in shape. In this case the outer peripheral portion of the secondary 33 is further away from the primary than the inner peripheral portion; thereby producing a flow upwardly through the conduit 35 into the reservoir 36 accompanied by return flow through the conduit 37.

50 In the modification shown in Fig. 6 both the primary inducing winding 38 and the secondary 39 are dished in a direction away from each other so that a maximum pressure is set up at the inner periphery of the secondary, causing a discharge of fluid through

the conduit 40 and a return flow from the reservoir 41 into the secondary 39 through the conduit 42.

In each of the modifications shown and described, it will be seen that the secondary 70 may be divided by imaginary surfaces, parallel to the direction of flow of secondary current, into complete circuit current-carrying elements or parts, of varying inductive relationships with the primary, with provision for direct communication between a part of relatively high inductive relationship and an auxiliary charge containing reservoir, and also between a part of relatively low inductive relationship and the reservoir. A circulation of charge, from the part of the secondary of lower inductive relationship to the reservoir, returning from the reservoir to the part of higher inductive relationship, is generated by a difference in fluid pressure 85 due to the electromagnetic repulsion between primary and secondary, this fluid pressure being greater for those parts of the secondary which are in lower inductive relationship with the primary. 90

What I claim as new and desire to secure by Letters Patent of the United States is—

1. An induction furnace comprising a primary winding, a refractory receptacle providing a looped cavity adapted to contain a liquid charge constituting a secondary, the primary and secondary being structurally so related that the spacing from the primary of sections of the secondary in planes passing through the axis of the primary increases progressively from one end of the sections to the other, and a passage external to said secondary through which charge may circulate between portions of the secondary spaced different distances from the primary. 105

2. An induction furnace comprising a magnetic core, a primary winding inter-linked therewith, refractory walls providing a cavity adapted to contain a molten charge which constitutes a secondary, said primary and secondary being arranged substantially coaxial with respect to said core and being so shaped that their adjoining sides are diverging, and means for permitting the flow of charge external to said secondary between regions of the secondary spaced different distances from the primary. 110 115

3. An induction furnace comprising a core, a primary winding, a looped cavity for containing a molten charge constituting a secondary in inductive relationship with the primary, the primary or secondary being of frusto-conical form, and structurally so related to each other that their adjacent surfaces are diverging, and a conduit external 120 to said cavity between regions spaced different distances from the primary. 125

4. An induction furnace comprising a primary winding, refractory walls providing a looped cavity adapted to contain a 120

- charge interlinked as a secondary with said primary, one of said primary and secondary being cylindrical and the other frusto-conical, and means external to said secondary for conveying charge between regions of the secondary spaced apart different distances from the primary.
5. An induction furnace comprising a magnetic core, a primary coil, a refractory 10 container providing a cavity interlinked with said primary coil and adapted to contain a charge constituting a secondary coil, said coils being arranged coaxially and being so shaped that their adjoining surfaces 15 diverge along their common axis, and means for conveying charge between regions of the secondary which are spaced different distances from the primary.
6. An induction furnace comprising a core, a primary winding thereon, a furnace 20 structure having refractory walls providing a cavity adapted to contain a fluid secondary magnetically interlinked with said primary, at least one of primary and secondary 25 having a frusto-conical shape thereby providing a progressively increasing spacing from one end of a transverse section thereof to the other, a reservoir, and conduits communicating between said reservoir and different regions of said cavity which 30 are spaced unequally from the primary in which a difference of fluid pressure exists by electromagnetic repulsion.
7. An induction furnace comprising a core, a primary winding and a receptacle 35 for containing charge, said receptacle including a reservoir and communicating therewith, a looped cavity within which a portion of the charge constitutes a closed 40 secondary, at least one of said elements being frusto-conical in shape, said elements being structurally so related that the surfaces of the primary and secondary which are adjacent to each other are diverging, so 45 that the distance from the primary to the secondary varies gradually from one end to the other of an oblong transverse section of the secondary, and conduits between the secondary cavity and the reservoir whereby 50 fluid charge can flow from the end of such transverse sections of the secondary cavity, which is more remote from the primary to the reservoir, and return from the reservoir to the end of the secondary which is closer 55 to the primary.

In witness whereof I have hereunto set my hand this 18th day of April, 1928.

JAMES M. WEED.
